UNITED STATES PATENT OFFICE.

RICHARD F. PIATT, OF LOUISVILLE, KENTUCKY.

CONDENSER AND HEATER.

SPECIFICATION forming part of Letters Patent No. 720,614, dated February 17, 1903.

Application filed June 5, 1902. Serial No. 110,397. (No model.)

To all whom it may concern:

Be it known that I, RICHARD F. PIATT, a citizen of the United States, residing at Louisville, in the county of Jefferson, State of Kentucky, have invented a new and useful Improvement in Condensers and Heaters, which improvement is fully set forth in the following specification and the accompanying drawings.

10 My invention relates to an improvement generally in that class of condensers and heaters usually constructed in the form of return-bend pipe-coils, although parts of the construction I employ are also suitable for use 15 with ordinary tubular condensers and heaters, and it is my intention in this application to claim as an improvement the application of such parts to the tubular form of construction.

20 In ordinary condensers and heaters constructed in the form of return-bend pipe-coils one pipe is placed within another larger pipe, and a number of pipes so placed are connected at their ends by means of special return-bend 25 fittings arranged to form return-bend coils wherein the outer or larger pipe is made continuous and the inner or smaller pipe is also made continuous, forming two independent passages, one within the other, for the con- 30 duction of liquid or gases. The liquid or gas to be heated or cooled is passed through one of these passages, and the liquid or gas which is used to produce the heat or cold in the other liquid or gas is passed through the other 35 passage. When such an apparatus is used for condensing steam or in cooling hot gases or liquids by means of cold water or for heating water by means of steam, lime or other solids held in solution by the water are sepa- 40 rated from the water by the heat and deposited on the surfaces of the pipe. The lime or other solids so deposited stop up the pas- 45 sages and interfere with the efficiency and usefulness of the condenser or heater and make it necessary to discontinue the use of the apparatus or of sections of it for the purpose of removing the deposits.

In tubular condensers and heaters where water is passed through tubes the same de- 50 posits occur, and the use of the heater or condenser must be discontinued while the deposits are being removed.

My invention relates to an improvement in the manner of constructing condensers and heaters to permit of the separation of each 55 tube for the double purpose, first, of cleaning or inspection without in any way interfering with any other tube or the operation of the apparatus; secondly, of lessening the surface of the outer tube which is exposed to the at- 60mosphere in comparison with the surfaces of the inner pipes.

The accompanying drawing represents a partial side elevation and a partial vertical section of a return-bend fitting embodying the 65 principles of my invention, the fitting being one of a coil.

A A' are metal tubes entering the return-bend fitting F. These tubes are threaded and have retaining-collars E. Packing-rings L, 70 of rubber or other suitable material, are held in place by the gland-casting D. Two or more metal pipes B B' are placed within the larger tubes A A', passing through the connecting-port N of the return-bend casting F and 75 through the back of the casting. Rubber disks or disks of suitable packing material M are placed in recesses formed in the back of the return-bend casting F. These packing-disks are perforated for the pipes B B' and are 80 held in place by the casting G, which forms a packing-gland for each of the pipes B B', also in connection with the plate H, the connect- 85 ing-port O connecting the pipes B with B'. Through the plate H are hollow plugs oppo- 90 site each of the pipes B B'. These hollow plugs are fitted with the solid plugs R, and when they are screwed to the seats P in casting G and the plugs R are removed these hollow plugs close off pipes B B' from the port O and 95 permit of the pipes B B' being cleaned or in- spected.

Lugs are formed on the return-bend casting F. Threaded bolts C are held by these lugs by means of nuts. Other nuts on the 95 bolts C retain the adjustable packing-gland D in position and also attach the return-bend fitting rigidly to the large outer tubes A A', the threaded collars E on the large outer tubes A A' serving as shoulders for the re- 100 turn-bend casting F and permitting of the adjustment of the packing-rings L without disturbing the position of the return-bend casting F. Still other nuts on the bolts C retain

the packing-gland and port-casting G and the plate H and permit of the adjustment of the packing-disks M.

Lugs K are formed on the top and bottom 5 and on each side of the return-bend casting F for the purpose of bolting together a number of return-bend fittings to make up a return-bend coil.

End fittings similar to one-half of the 10 turn-bend fittings shown in the accompanying drawing, but suitably constructed with holes for pipe connections communicating with the ports N and O, are used for the ends of return-bend coils.

15 In tubular condensers or heaters where a single outer shell contains many small tubes the construction is the same as the end fittings of the return-bend coil.

In operation a liquid or gas is caused to 20 pass through the large outer tubes A A', which communicate with each other at each return-bend fitting through the ports N. Another liquid or gas is caused to pass through the small inner pipes B B', which communicate 25 with each other at each return-bend fitting through the ports O and heat or cold is transferred from one liquid or gas to the other liquid or gas through the walls of the small inner pipes B B'. When used as a steam-condenser or as an ammonia-condenser, or for 30

similar purposes where the cooling agent is usually water, which may contain solids which will be deposited on the walls of the pipe, the cooling - water may be passed through the small inner pipes B B', as these pipes can 35 each be cut off from communication with the ports O at each end of the pipe by means of the hollow plugs J, which will admit of cleaning the small inner pipes one at a time without interfering with the operation of the apparatus as a whole. 40

Having thus described my invention, what I claim as new, and desire to secure by Letters Patent, is—

In a condenser and heater having several 45 small pipes contained within a larger tube, all passing through fixed heads, other gland-heads forming in connection with removable plates, ports for connecting the corresponding ends of all small pipes; seats formed in 50 each perforation of the gland-heads opposite each small pipe; and short hollow plugs, plugged at their outer ends with removable solid plugs and screwed through the removable plates opposite each seat, all substantially as described. 55
